FISHING LURE

William D. Storm, P.O. Box 265,
Norman, Okla. 73069

Filed May 27, 1970, Ser. No. 23,169

Term of patent 14 years

Int. Cl. D22—05

U.S. Cl. D22—27

FIG. 1 is a side elevation of a fishing lure showing my new design, all of the elements shown in broken lines being for illustrative purposes only.

FIG. 2 is a top plan view of the fishing lure depicted in FIG. 1.

FIG. 3 is a bottom plan view of the fishing lure depicted in FIG. 1.

FIG. 4 is a front elevational view of the fishing lure depicted in FIG. 1; and

FIG. 5 is a rear elevational view of the fishing lure depicted in FIG. 1.

I claim:

The ornamental design for a fishing lure, substantially as shown and described.
